ATTORNEY

UNITED STATES PATENT OFFICE.

JAN BARTUZEL, OF YOUNGSTOWN, OHIO.

NEWSPAPER-HOLDER.

1,352,398.

Specification of Letters Patent.

Patented Sept. 7, 1920.

Application filed October 15, 1919. Serial No. 330,780.

To all whom it may concern:

Be it known that I, JAN BARTUZEL, a citizen of Poland, residing at Youngstown, county of Mahoning, and State of Ohio, 5 have invented certain new and useful Improvements in Newspaper-Holders, of which the following is a specification.

This invention has for its object the provision of means for holding a paper when 10 in an open or spread condition so that it can be easily read.

A further object is to provide means combined with the holder whereby the marginal edges upon one or both sides of the paper 15 may be secured to the holder or released therefrom in a convenient manner.

These objects are attained by the novel construction and combination of parts hereinafter described and shown in the accompanying drawings, forming a material part 20 of this disclosure, and in which—

Figure 1 is a front elevational view showing a paper holder made in accordance with the invention.

Fig. 2 is a partial side elevational view of the same.

Fig. 3 is a transverse sectional view taken on line 3—3 of Figs. 1 and 4, drawn to an enlarged scale, and

Fig. 4 is a fragmentary longitudinal sectional view taken on line 4—4 of Fig. 3.

Referring to the drawings in detail, the numeral 10 designates a handle adapted to be conveniently operated, from which extends a shank 11, having at its upper end a plate 12, adapted to act as one of the support elements for newspaper.

Fixed upon the shank 10, at spaced intervals along its length, are a pair of clips 14 40 in which are hingedly engaged oppositely disposed bars 15, these bars being connected at each end by semi-circular curves 16, with spaced parallel bars 17. These elements form the frame for supporting the 45 paper and constitute in effect a pair of flat oval wire frames which may be folded closely together or disposed in a horizontal plane, as indicated best in Fig. 1.

Secured to one of the bars 17 by other 50 clips 18 is a rod 23 having an enlarged forked head 22 at its upper end, and pivoted upon a pin 21 between the forks 22, is a

head 20 formed on a rod 19 extending coincidently with the rod 23.

The lower end of the rod 23 is pivotally 55 engaged by a pin 24, between the two parallel sides 25, of a U shaped head 26, the head containing in its outer surface a plurality of indentations 27, and slidably engaged to move longitudinally upon the head 26 is a 60 rectangular sleeve 28, provided with an enlarged circular operating knob 29.

Formed in the head is an internal recess 30, in which is disposed a flat semi-elliptical spring 31, adapted to engage any of the several recesses 27, so as to hold the sleeve in position relative to the head 26.

In operation, the margin of the newspaper is placed between the rods 19 and 23, which are then closed tightly together, the 70 head 26 is rotated on the pin 24, so that the lower ends of the rods 20 and 23 enter the space between the sides 25, whereupon the sleeve 28 is moved so as to engage over the ends of the rod and held in an adjusted position by the spring 31, clamping the rods together with the paper between, thereby holding the paper expanded over the frame elements in an obvious manner.

From the foregoing it will be seen that a 80 neat and effective device has been presented which will effectively hold a newspaper or like sheet suspended in position to be conveniently read by a person manipulating the handle 10, and that the edge of the paper 85 may be clamped or released by maneuvering the sleeve 28 in a manner which will be clearly apparent.

I claim—

1. A paper holder comprising a stem, a 90 handle extending therefrom, a plate element formed on the end of said handle, clips secured on said stem, a pair of open wire frames hingedly engaged in said clips, a rod engaged with the outer end of one of said 95 frames, a second rod pivoted with the first named rod, a head adapted to engage the two rods when in close relation, and a slide movable over said head whereby said rods are held in said head.

2. A newspaper holder comprising a handle, a frame having distensible elements arranged in parallel and adapted to extend oppositely outward from the handle, a rod se-

cured to one of the lateral elements of said frame, a second rod pivoted with the first named rod, a body pivoted at the opposite end of the first named rod, said body having a recess receptive of the lower end of each of said rods, a slide movable on said hollow body, and a detent carried by said slide en-

gageable in recesses formed in said body, said slide being movable so as to confine said rods within said body.

In testimony whereof I have affixed my signature.

JAN BARTUZEL.
